UNITED STATES PATENT OFFICE.

ANTONIN MONTEILHET, OF PARIS, FRANCE, ASSIGNOR TO SOCIETE ANONYME DES
TELEGRAPHES EDOUARD BELIN, OF PARIS, FRANCE.

METHOD OF AND APPARATUS FOR FACSIMILE TELEGRAPHY.

Application filed September 15, 1918. Serial No. 739,928.

(GRANTED UNDER THE PROVISIONS OF THE ACT OF MARCH 3, 1921, 41 STAT. L., 1818.)

To all whom it may concern:

Be it known that I, ANTONIN MONTEILHET, citizen of the Republic of France, residing in Paris, in the Republic of France, have invented certain new and useful Improvements in a Method of and Apparatus for Facsimile Telegraphy, of which the following is a specification.

The present invention relates to a method of and apparatus for the transmitting and receiving by aid of the existing line or wireless telegraphic stations, messages, designs of every kind, clichés, reliefs, photographs, and the like, excepting, however, ordinary 15 signatures.

According to the invention energy impulses are sent out from the transmitting station both in the case of wireless and line telegraphy which are always of the same 20 value, that is to say are always constant in value. The transmitting station has a local circuit carrying a variable electric current which on reaching a predetermined value sends out similar energy impulses which are 25 constant in value. The receiving station is also provided with a local circuit which is closed on the reception of the constant energy impulse and is closed for a time during which the impulse is sent. The actual 30 receiving apparatus is preferably of the optical kind. The local circuit in the transmitting station only cooperates with the main circuit when a regular periodic variable in the local circuit attains a value corresponding to a certain particular value of 35 an adjustable variable in the said local circuit. The receiver may be provided with a similar periodic variable driven synchronously with that in the transmitting circuit

40 in which case the signal received would depend on the time at which the impulse was received for its value as regards the current, the current varying from this value to a predetermined fixed value during the sending 45 of the impulse, each impulse naturally lasting for a very short time. Or again this synchronized periodic variable need not be employed, the signal received depending entirely on the time during which the signal 50 lasts.

In the drawing there is diagrammatically represented a transmitting and receiving device for the transmission of clichés, draw-

ings or the like by means of ordinary wireless transmission.

At the transmitting station there is a local circuit including a battery or source of current S, the apparatus A, for example, as disclosed in the prior patent to E. Belin, No. 915,154, by which the variations of the current in the circuit are created by the passage of the document therethrough, and further a relay R is included controlling a closing switch allowing the emission of waves by the antenna L, and finally the variable resistance c functioning as in the manner described below.

During a certain period of time during which the whole range of the variable resistance c is covered by the sliding contact, a 70 point, or more preferably, a very small portion of the document is explored or placed in circuit by means of an appropriate contact in series with the circuit. During this exploration and consequent upon the nature 75 of the document and of the member which translates the values (reliefs by means of a rheostat or microphone, or again directly by means of an insulated selenium cell, or through a photographic cliché, etc.), the resistance of the local circuit is varied and a contact moves over the variable resistance in such manner that at last it will arrive at a condition when the algebraical sum of the two variations are such that the relay R can 80 be actuated. The emission of a wave takes place at this actual moment. It is evident that the faster the resistance operates, the greater can be the speed or degree of fineness of the exploration and more frequent 85 will be the emissions of waves by the antenna.

At the receiving station on the antenna L' there is arranged a relay R' or like arrangement which, at the receiving of a wave by 90 the antenna, closes a local circuit S'. In this circuit there is included a variable resistance c' and the registering or indicating apparatus E, such as a galvanometer or like sensitive member. The moving contact of the 100 variable resistance has a similar movement to that of the resistance c in the local transmitting circuit. The two movements are synchronous and may be, as desired, either in the same direction or in opposite directions so as to produce in their respective cir-

cuits similar or contrary effects. On a wave arriving and causing the closing of the local receiving circuit at the moment when the resistance c' lies at a value similar to that of the resistance c the resistance of the local circuit is varied proportionally to the resistance introduced into the circuit by the element explored in the local transmitting circuit; consequently the receiver reproduces or faithfully translates by its own mechanism the image or the document passed through the transmitter.

Assuming ρ is the maximum value of the variable resistance c in the local transmitting circuit; and that α is the maximum resistance of the whole circuit which includes the relay, the maximum value of resistance due to the signal arrangement, and the maximum value ρ of the variable resistance; and ω equals the resistance in the circuit at which the relay R operates, then in order that the relay will be operated by varying the cursor, it is essential that $\alpha - \rho$ is at least equal to ω .

Now if due to the exploring of a relief (or to the insertion of an insulated selenium cell), the maximum resistance of the local circuit is diminished from the value α by a quantity β (naturally ρ must be greater than the maximum value of β), the relay will operate when $\omega = (\alpha - \beta) - (\rho - \beta)$ that is to say when the moving contact of the variable resistance of the transmitting circuit is at the value $\rho - \beta$.

The moving contact of the variable resistance of the local receiving circuit will be at an identical value $\rho' - \beta'$ that is to say the local receiving circuit which had a resistance $\alpha' - \rho'$ will then have a resistance $\alpha' - (\rho' - \beta')$.

It therefore registers or indicates a variation β' (where α' , β' , and ρ' indicate, in the receiving circuit, the corresponding proportional values of their respective significations in the transmitting circuit).

In considering the point which explores the document for obtaining the signals it is necessary to point out that the whole of the variable resistance is run off by the cursor in a very short time t of the minute exploration covered by one signal. During this time t the cursor will reach the point at which the relay operates say at the end of the time dt it follows that the signal will be transmitted during a time $(t - dt)$. On the arrival of the signal the relay at the receiving station is operated at the instant dt and the local circuit will remain closed during the same interval of time $(t - dt)$. As the variable resistances are operated synchronously the local circuit of the receiver will operate for exactly the same time and with the same conditions of current as are taking place in the local transmitting circuit.

The synchronism of the varying resist-

ances may be assured in any desired manner at each revolution or after any given number of revolutions.

It is evident that the variations β β' can be equal or proportional. Also they may be of inverse sign. Further, that the action of the resistances c c' may take place by diminishing or increasing the resistance. Further, that the exploring of the picture or the like may be continuous or interrupted, according to the period taken to cover the variable resistance c without leaving the scope of the present invention.

The present invention has the characteristic feature of using for radio-telegraphic transmission waves or emissions of constant degree combined with a local circuit having a variable resistance at the transmitter and at the receiving stations, the variations in the one variable resistance being synchronous with those of the other the two being equal, proportional, similar, or inverse.

The balancing resistance may, if desired, be eliminated together with the moving contact of the receiving circuit. In this case the scale of tints which is employed to record the varying signals received, would be likewise eliminated and replaced by a slotted diaphragm similar to those used in portrait photography, which only allows a full signal or no signal at all to be recorded and not a signal the strength of which varies. As long as the value ω is not attained in the transmitting circuit, the spot will remain either outside the slot or on the slot of the diaphragm according to the sense of the picture to be obtained. At the moment when the value ω is attained the spot takes up the contrary positions and the different tonalities or degrees of value will result not so much owing to the greater or less degree of extinction of the luminous rays, but owing to the greater or less duration of their action, which comes to the same thing.

It is known that the blackening of a photographic sensitive layer is proportional not to the quantity of light received but to the logarithm of this quantity of light and this factor should be taken into account in the construction or selection of the balancing resistance of the transmitting circuit.

The mode of transmission may evidently be applied in either of the two forms of reception to line telegraphy, the wave producing apparatus and the antennæ L and L' being then replaced by a source of current and the line wire.

It has been found that an apparatus of this kind may be very advantageously used for transmission of telephotography over very long distances by a single wire having an earth return thus eliminating the energy wasted in the line for actuating the receiving apparatus, the arrangement merely requiring slight detail alterations.

Having now particularly described and ascertained the nature of the said invention and in what manner the same is to be performed, I declare that what I claim is:

- 5 1. In an arrangement for transmitting messages or designs, such as photographs, clichés and the like, the combination of synchronized means for periodically varying the local circuit of both the transmitter and 10 the receiver, and means for sending a signal energy impulse of constant value from the transmitter to the receiver when the total temporary value of the variable in the local transmitter circuit reaches a predetermined value corresponding to the signal 15 to be transmitted.

2. An arrangement for transmitting messages or designs, such as photographs, clichés and the like, as claimed in claim 1 20 in which the energy impulses are transmitted by wireless telegraphy.

3. In a system for transmitting facsimiles by telegraph, the combination with a transmitting station having a periodically varying 25 resistance in the local circuit thereof, of a receiving station having a periodical varying resistance in its local circuit in synchronism with that of the transmitting station, and means energizing the local circuit 30 of the receiving station to indicate the value of the variable at the transmitter when a signal impulse of constant value is received by the main circuit substantially as described.

35 4. In a wireless transmitter apparatus for transmitting facsimiles by telegraphy, the combination of means for translating the facsimile into a certain value of resistance in the local circuit of the transmitter, a resistance in said circuit variable periodically between certain values, and a relay in said circuit arranged to be energized when the total resistance of the local circuit attains a certain predetermined value after a lapse 40 of time varying according to the signal to

be transmitted, thereby causing the transmission of a definite constant signal impulse by the main circuit.

5. In a system for wireless transmission of facsimiles, the combination with a transmitting station having a periodically varying resistance in its local circuit, a resistance in said circuit set to a temporary value dependent upon the signal to be transmitted, and means operable upon the attaining of 50 a predetermined total value of resistance in said local circuit to send a constant signal impulse, of a receiving station having a local circuit and a relay having contacts in said circuit adapted to close the same and 55 energized by the aerial circuit.

6. In a system for wireless transmission of facsimiles, as claimed in claim 3, combined with a relay at the receiving station which is adapted to close the local circuit 60 upon the reception of a signal impulse of constant value from the main circuit.

7. A system for wireless transmission of facsimiles embodying a local circuit, means for producing a regular periodic variable in 70 the local circuit, an adjustable variable in said local circuit, and means to effect the main circuit to cause the transmission of a constant energy impulse when the regular periodic variable in the local circuit attains 75 a value corresponding to a certain particular value of the adjustable variable in said circuit.

8. A system for wireless transmission of facsimiles as claimed in claim 7, wherein the 80 value of the variable transmitted depends upon the duration of the signal impulse.

In witness whereof I have hereunto signed my name this first day of September, 1913, in the presence of two subscribing witnesses. 85

ANTONIN MONTEILHET.
